UNITED STATES PATENT OFFICE.

HENRY F. BARNING, OF JERSEY CITY, NEW JERSEY.

BREECH-LOADING GUN.

SPECIFICATION forming part of Letters Patent No. 794,770, dated July 18, 1905.

Application filed November 21, 1904. Serial No. 233,593.

To all whom it may concern:

Be it known that I, HENRY F. BARNING, a citizen of the United States, residing at Jersey City, in the county of Hudson and State 5 of New Jersey, have invented certain new and useful Improvements in Breech-Loading Guns, of which the following is a specification, such as will enable those skilled in the art to which it appertains to make and use the 10 same.

This invention relates to guns of the breech-loading class, and particularly to rifles of this class; and the object thereof is to provide such a gun in which the usual finger-lever is 15 employed and by the operation of which a breech-block is operated vertically into or out of operative position with reference to the barrel of said gun, a further object being to provide a gun of this class which is automatically set at full-cock in the operation of removing said breech-block from operative position and which is cocked before said breech-block is moved, thereby preventing injury to 20 the firing-pin or other portions connected with said breech-block, a still further object being to provide a gun of this kind or class which dispenses with the hammer usually employed, said hammer being replaced by a longitudinally-movable firing-pin, the operation of 25 which when the gun is discharged does not in any way affect the user's aim through vibration imparted in a direction different than the aim of said gun.

The invention is fully disclosed in the following specification, of which the accompanying drawings form a part, in which the separate parts of my improvement are designated by suitable reference characters in each of the views, and in which—

Figure 1 is a longitudinally vertical section of a rifle constructed according to my invention and showing the operative parts in positions which they occupy after the discharge of said rifle; Fig. 2, a view similar to Fig. 1, 40 but showing the parts in their extreme lower positions, which they occupy during the loading of said rifle or the insertion of a cartridge in the barrel thereof; Fig. 3, a section on the line 3 3 of Fig. 1; Fig. 4, an enlarged section 45 on the line 4 4 of Fig. 1; Fig. 5, an enlarged

face view of the forward end of a breech-block which I employ; and Fig. 6, an enlarged view of the firing-pin similar to that shown in Fig. 1, but showing a slight modification thereof, said modification being the adaptation thereof 55 to rim-fire cartridges, whereas Fig. 1 is adapted for center-fire cartridges.

In the drawings forming a part of this specification I have shown at *a* a portion of the barrel of a rifle, which is screwed into a receiver *b*, which forms the body portion of the rifle and which contains the operative parts thereof, and also mounted in said receiver is a fore-arm tip *c*, which bears against the under side of the barrel *a* in the usual manner, 60 and inserted in the receiver *b* and at the rearward end thereof is a butt-stock *c'*, only a portion of which is shown, and the fore-arm tip *c* and butt-stock *c'* are composed of wood or other suitable material in the usual manner 65 and are secured to said receiver in the usual or any desired manner.

The barrel *a* is provided with a circular recess *a'* in the rearward end thereof, said recess being adapted to receive the flanged end 70 of a cartridge, and in the normal position of the parts of my improved rifle, as shown in Fig. 1, a firing-pin *d* is mounted directly at the rear and centrally thereof of the barrel *a*, and the firing-pin *d* consists of an annular 75 ring *d'*, mounted in a breech-block *e* and movable therein longitudinally of said barrel, and the casing *d''* is provided with a pointed end *d''*, which is screwed into the forward end of 80 said casing, and a strong coil-spring *d'* (hereinafter referred to as the "mainspring") is placed within the casing *d''* and is held therein by means of a pin *d''*, passing through slots *d''* on the sides of said casing and into the breech-block on either side of said casing, and, 85 as will be seen, when the casing *d''* is forced backwardly against the spring *d'* said spring is compressed because of the pin *d''*, said pin being independent of the casing *d''*, and when the casing *d''* is released in its backward position the mainspring *d'* forces said casing forwardly, and the pointed end *d''* passes through 90 a plate *e'*, secured in the forward end of the breech-block *e* by means of screws *e''*, as clearly shown in Fig. 5, and the plate *e'* may be re- 95 100

removed whenever desired and replaced by another permitting greater or less movement of the casing d^2 , or the plate e^2 by the turning of the screws e^3 may be adjusted to permit the 5 pointed end d^3 to project farther into the barrel a , if desired, or said plate e^2 may be replaced by one similar to that shown at e^4 in Fig. 6, in which the opening e^5 therethrough is placed nearer the periphery thereof, this 10 last-named plate e^4 to be used with rim-fire cartridges, and when so used the pointed end d^3 , employed in Figs. 1 to 5, inclusive, is replaced by one similar to that shown at d^7 in Fig. 6, this substitution of the plate e^2 or the 15 end d^3 being readily accomplished and without taking the gun apart, for, as will be seen in Fig. 2, if the fore-arm tip c be removed, a screw-driver or other tool may be inserted in the receiver b and the screws e^3 be taken out 20 if the breech-block e be lowered to its extreme position, as shown in Fig. 2.

The breech-block e consists of two side members e^6 , which operate in substantially vertical grooves b^2 in the inner sides of the receiver b and as clearly shown in Fig. 3, and the side members e^6 of the breech-block are preferably united or integral at their upper ends, thereby forming a bridge or cover over the casing d^2 , as clearly shown in Figs. 1 and 30 4. The casing d^2 is provided on its under side with a downwardly-projecting finger d^8 , rearwardly of which and at some distance therefrom is a shoulder d^9 , and when the casing d^2 is forced backwardly a lock-bolt f , pivoted with a shouldered end f^2 , and normally forced upwardly by a coil-spring f^3 , is adapted to engage the shoulder d^9 and hold the casing d^2 in its backward position. The lock-bolt f is slidably mounted in a casing f^4 , secured between the depending side members e^6 of the breech-block, and said bolt is provided adjacent to its lower end with a vertically-arranged recess f^5 , in which is mounted a lever f^6 , pivoted at f^7 , and if pressure be 40 brought to bear on the end f^8 of the lever f^6 the lock-bolt f is drawn downwardly, thereby releasing the shoulder f^2 from the shoulder d^9 , and the casing d^2 is forced forwardly by means of the mainspring d^4 .

50 Pivotedly mounted at g on the receiver b and within the same is a finger-lever g^2 , provided with a recess g^3 , in which the triggers h and i are adapted to operate, and the finger-lever g^2 is provided adjacent to its pivotal point g with two upwardly-directed members g^3 , between which is pivotally held a toggle-lever g^4 by means of a bolt g^5 passing therethrough and through said members g^3 , and the toggle-lever g^4 is pivotally connected with 55 the depending members e^6 of the breech-block e by means of a bolt g^6 , and when the finger-lever g^2 is operated downwardly and forwardly in the position shown in Fig. 2 the toggle-lever g^4 is first carried into the position 60 shown in dotted lines at g^7 , Fig. 2, at which

time the upper inclined surface of a nose g^8 of said toggle-lever bears against the finger d^8 of the casing d^2 , and the toggle-lever g^4 being firmly connected with the breech-block e the casing d^2 is forced backwardly by the 70 said movement of the toggle-lever g^4 and the finger-lever g^2 until the shoulder d^9 is engaged by the shoulder f^2 of the lock-bolt f , at which time the casing d^2 , which constitutes the firing-pin of the rifle, is cocked, and a 75 continued movement downwardly and forwardly of the finger-lever g^2 until the position shown in Fig. 2 is reached carries the breech-block e and its connected parts downwardly into the position shown in Fig. 2, at 80 which time said breech-block is completely below the recess a^2 of the barrel a , and a shell or cartridge may at this time be inserted in the barrel a , and when the finger-lever g^2 is brought to the position shown in Fig. 1, the 85 breech-block e is forced upwardly to the position shown in Fig. 1, and if the firing-pin had not previously been engaged by the lock-bolt f the said firing-pin is forced backwardly in the upward movement of the finger-lever g^2 , as will be seen, and the rifle will 90 at this time be cocked; but cocking thereof is usually accomplished in the first stage of the movement of the toggle-lever g^4 and the finger-lever g^2 previous to the downward movement of the breech-block e .

The plain trigger h , as shown in the drawings, is pivotally mounted in vertical side members h^2 within the receiver b and is provided with an operating-spring h^3 and with a 100 backwardly-directed pointed block h^4 , by which a forwardly-directed pointed end i^2 of the set-trigger i is adapted to be engaged, said set-trigger i being provided with a trigger-spring i^3 , and mounted pivotally between 10 the vertical members h^2 in the receiver b , as shown at h , is a striker k^2 , the rearward end k^3 of which is adapted to be struck by the outer end i^4 of the set-trigger i , and the forward end k^4 of said striker projects over the end f^8 of the lever f^6 , as plainly shown in Figs. 1 and 3, and when the set-trigger i is operated the parts assume the positions shown in Fig. 2, and when slight pressure is brought to bear on the plain trigger h the set-trigger 115 i is released therefrom and, springing upwardly, comes in contact with the striker k^2 , which in turn striking the end f^8 of the lever f^6 withdraws the lock-bolt f from its engagement with the firing-pin or casing d^2 thereof, and the rifle is thereby discharged, and upon 120 another downward movement of the finger-lever g^2 the rifle is again cocked and the breech-block carried to a position permitting the insertion of a fresh shell or cartridge. 125

In Figs. 1, 2, and 4 I have shown a safety device to be used in connection with my firing-pin and which consists of an eccentrically-pivoted disk m , mounted in the breech-block e directly above the casing d^2 of the firing- 130
